US00D961340S

(12) **United States Design Patent** (10) **Patent No.:** **US D961,340 S**
(45) **Date of Patent:** **** Aug. 23, 2022**

(54) **INVERTED BOTTLE HOLDER**

(71) Applicant: **Carl Hackley**, Charlotte, NC (US)

(72) Inventor: **Carl Hackley**, Charlotte, NC (US)

(**) Term: **15 Years**

(21) Appl. No.: **29/791,550**

(22) Filed: **Jan. 17, 2022**

Related U.S. Application Data

(63) Continuation-in-part of application No. 29/652,262, filed on Jun. 30, 2020, now Pat. No. Des. 942,224.

(57) **CLAIM**

The ornamental design for an inverted bottle holder, as shown and described.

DESCRIPTION

FIG. 1 is a perspective view of an inverted bottle holder, showing my new design;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof;

FIG. 5 is a bottom plan view thereof; and,

FIG. 6 is a perspective view thereof, shown in a used condition.

The broken lines showing a bottle in FIG. 6 depicts environmental subject matter that forms no part of the claimed design.

1 Claim, 4 Drawing Sheets
